Attest.

United States Patent Office.

J. G. SPRAGUE, OF LEXINGTON, ILLINOIS.

Letters Patent No. 99,490, dated February 1, 1870.

COMBINED HEDGE-TRIMMER AND STALK-CUTTER.

The Schedule referred to in these Letters Patent and making part of the same.

To all whom it may concern:

Be it known that I, J. G. SPRAGUE, of Lexington, in the county of McLean, and in the State of Illinois, have invented certain new and useful Improvements in Hedge-Trimmer and Stalk-Cutters; and do hereby declare that the following is a full, clear, and exact description thereof, reference being had to the accompanying drawings, and to the letters of reference marked thereon, making a part of this specification.

The nature of my invention consists in the construction and general arrangement of a machine for cutting corn-stalks and trimming hedges.

In order to enable others skilled in the art to which my invention appertains, to make and use the same, I will now proceed to describe its construction and operation, referring to the annexed drawings, in which—

Figure 1 is a plan view, and

Figure 2 is a longitudinal vertical section of my machine.

A A represent the wheels, mounted upon the ends of the axle B, from the front side of which two beams, C C, project forward, said beams being bent slightly inward, as shown in fig. 1, so as to connect at their front ends.

On top of the beams C C, immediately in front of the axle B, is a cross-beam, D, from which rise standards E, supporting another beam, G, running parallel with the cross-beam D, and provided on its upper side with a seat, F, for the driver.

The axle B, beams C, and standards E, are connected by means of curved braces H, as seen in fig. 2.

At the point where the beams C C are joined together, a standard, I, passes through them, which standard is at its lower end provided with a small wheel, J, on which thus the front end of the machine rests.

On the upper end of the standard I, is a socket, a, in which is inserted the governor K, which should be turned, so that its outer rim b will be within reach of the driver from his seat F, enabling him to operate the same with the hand, or with the foot, whichever may be deemed most advantageous.

At the front end of the beams C is a bent rod, d, forming a loop or ring at its front end, said ring being secured to the tongue L.

The tongue L is split or forked at the rear end, embracing the front ends of the beams C, and inserted in sockets e e, one on each side of said beams.

The rod d lies on the upper side of the tongue, a spring-bar, i, from the tongue, projecting through the loop or ring, and this loop or ring secured by a staple, f.

In front of the driver's seat F, on the beams C C, are standards M M, secured to the beams by means of keys g g, in such a manner that they can be readily removed.

Between the standards M M, the treadle N is piv-

oted, said treadle being at a suitable height to be operated by the driver's foot.

At the front end of the treadle N, on each side, is pivoted a bar, O, which passes downward through a slot in the beam C, and is at its lower end pivoted to a curved or bent bar, P. This bar P is slotted at its upper end, and is attached to the inner side of the beam C by means of a screw, h, so that the bar can slide freely up and down.

Between the lower ends of the bars P P is pivoted a shaft, K, having a polygonal-shaped enlargement, S, at each end.

From each side of the enlargements S S extends an arm, k, and to the arms k k are secured the knives m m running parallel with the shaft R, and braced by braces n n, said knives being of sufficient length to cut two rows, instead of one row, as is usually the case.

To the bent bars P P are attached arms o o, which extend in front of the cutter, to guide or bring the stalks in contact with the knives.

It will readily be seen that with a machine thus constructed, corn-stalks will easily be cut off, and the driver can, by means of the treadle N, raise or lower the cutter at will.

When it is desired to use the machine as a hedge-trimmer, the following changes are made:

The standards M M, with the treadle N, and the cutter, are removed, which is readily done by taking out the keys g g and screws h h, also the bolts that pivot the bars O O to the treadle. The tongue L and governor K are also removed.

On the left hand of the seat-supporting bar G are fixed suitable journal-bearings, for supporting the knife T, when it is desired to trim the sides of the hedge. The knife-handle is at a suitable point provided with journals r r, for insertion in the journal-bearings mentioned, the knife itself extending in front, and the handle in rear of said bar G.

At the lower end of the left standard E is a bar, U, inclined downward and toward the rear, and braced by a brace, V, which at its outer lower end forms a hook, to which a cord, p, is secured. This cord passes upward around a pulley, in the end of the knife-handle, and then downward again, around a pulley in the rear end of the beam U, then forward through a loop, s, on the inside of the front ends of the beams C C. The knife is to be operated by a man at the front end of the machine, pulling on the end of the rope p, assisted by another man at the rear end, who takes hold of the knife-handle, whenever he can reach it. At suitable points on the beams C C are standards W, connected by a bar, t, having arms v v, as seen in fig. 1.

On the top of the standard W, on the right side, is placed a bar, X, which is attached to the right standard E, and at its outer or forward end, is pivoted the

handle of a fork, *y*. The branches, &c., cut off by the knife *T*, fall down on the fork, or rather rake *y*, and are easily thrown off on one side.

When it is desired to trim the top of the hedge, the knife *T* is placed with one of its journals in a bar, *w*, on top of the bar *G*, and the rope *p* is secured to the right end of said bar *G*, then around the pulley in the end of the knife-handle, then through a pulley, near the right end of the bar *G*, and then through the loop *s*, as before.

When used as a hedge-trimmer, the machine is propelled by the man in the front, by means of a staff or lever, *Z*, with point, which said staff passes through the ring *d*, the ground being employed as a fulcrum to the lever or staff.

The knife *T*, standards *W W*, and bar *X*, are readily removed, so as to attach the parts which form the stalk-cutter.

Having thus fully described my invention,

What I claim as new, and desire to secure by Letters Patent, is—

1. The arrangement of the shaft *R*, arms *k k*, knives *m m*, braces *n n*, bars *P P*, with guides *o o*, arms *O O*, and treadle *N*, all constructed as described, so as to be readily removed from the carriage, substantially as herein set forth.

2. The arrangement of the tongue *L*, bar *i*, staple *f*, boxes *e e*, and rod *d*, all as shown and described.

3. In combination with the cross-bar *G*, the knife *T*, when both are so arranged with journals and journal-boxes, or their equivalents, that the knife can be operated both laterally and perpendicularly, substantially as and for the purposes herein set forth.

4. The combination and arrangement of the standards *W W*, bar *t*, arms *v v*, bar *x*, and fork *y*, substantially as and for the purposes herein set forth.

In testimony that I claim the foregoing, I have hereunto set my hand, this 15th day of September, 1869.

J. G. SPRAGUE.
